(57) **CLAIM**

The ornamental design for a digital microscope, as shown and described.

DESCRIPTION

FIG. 1 is a front elevational view thereof of a digital microscope showing my new design;

FIG. 2 is a rear elevational view thereof; and

FIG. 3 is a left side view thereof;

FIG. 4 is a right side view thereof;

FIG. 5 is a top plan view thereof;

FIG. 6 is a bottom plan view thereof;

FIG. 7 is a perspective view thereof of a digital microscope showing my new design; and,

FIG. 8 is another perspective view thereof showing the screen is closed.

The broken lines in the figures are for the purposes of illustrating portions of the digital microscope, which form no part of the claimed design.

1 Claim, 8 Drawing Sheets
